UNITED STATES PATENT OFFICE

JOHN KIRKPATRICK, OF CLARKSBURG, WEST VIRGINIA, ASSIGNOR TO HAZEL-ATLAS
GLASS CO., OF WHEELING, WEST VIRGINIA, A CORPORATION OF WEST VIRGINIA

DESIGN FOR A TUMBLER

Application filed April 5, 1930. Serial No. 35,170. Term of patent 7 years.

To all whom it may concern:

Be it known that I, JOHN KIRKPATRICK, a citizen of the United States, residing at Clarksburg, in the county of Harrison and State of West Virginia, have invented a new, original, and ornamental Design for Tumblers, of which the following is a specification, reference being had to the accompanying drawing, forming part thereof.

Figure 1 is a perspective view of a tumbler, showing my new design;

Figure 2 is a fragmentary sectional view taken on line 2—2 of Figure 1; and

Figure 3 is a fragmentary sectional view taken on line 3—3 of Figure 1.

I claim:

The ornamental design for a tumbler, as shown.

JOHN KIRKPATRICK.
